UNITED STATES PATENT OFFICE.

FREDERICK L. ALLEY, OF LYNN, MASSACHUSETTS.

TAKE-UP MECHANISM.

SPECIFICATION forming part of Letters Patent No. 595,802, dated December 21, 1897.

Application filed October 20, 1896. Serial No. 609,472. (No model.)

To all whom it may concern:

Be it known that I, FREDERICK L. ALLEY, a citizen of the United States, residing at Lynn, in the county of Essex and State of Massachusetts, have invented certain new and useful Improvements in Take-Up Mechanisms; and I do hereby declare the following to be a full, clear, and exact description of the invention, such as will enable others skilled in the art to 10 which it appertains to make and use the same.

The present invention relates to take-up mechanisms for sewing-machines, and more particularly to that class of take-ups arranged to be movable about a center having either a 15 rotary or oscillating movement, the present invention consisting in an improved arrangement of the thread-guard whereby the thread is retained upon the take-up.

The invention as applied to a rotary take-up is illustrated in the accompanying drawings, in which—

Figure 1 represents in side elevation the take-up in its lowest position. Figs. 2 and 3 are front views of the improved take-up, showing the take-up in different positions along its path of rotation and different positions of the 25 actuating mechanism which imparts a variable angular velocity to the take-up, said figures further illustrating, diagrammatically, 30 the relative positions of the shuttle, material, thread-guides, and tension.

In the drawings, A represents the take-up, which comprises a rotary arm a, upon which is mounted a thread-carrier a', conveniently 35 provided with a thread-roll a², about which runs the thread 8.

The thread 8 is held upon the thread-roll a² by what I term a "thread-guard" a³, which, as shown, partially surrounds and overlaps 40 the thread-roll a². In order that the thread 8 may not become wound about or caught upon the thread-guard a³ and so impede the 45 successful operation of the device or the passage of thread through same, I have arranged the thread-guard a³ to present the same side in the direction of the pull of the thread for any position of the arm a or to always cause it to remain up and over the take-up. I accomplish the result above suggested by arranging thread-guard a³ to rotate about an

axis of its own, making one revolution about such axis for every rotation of the arm a.

As shown in the drawings, the thread-guard a³ is secured to the carrier a', which is mounted upon and rotates with a short shaft projected 55 through a suitable bearing a⁴ in the arm a and carrying on the opposite side thereof a gear 9, meshing with a gear 10, connected by a short shaft mounted in a suitable bearing a⁵ on arm a with a gear 11, meshing with a gear 12 on 60 sleeve 13, which surrounds the shaft B, by which the arm a is rotated, and is fixedly secured to a fixed portion 14 of the machine.

In the diagrammatical portions of Figs. 2 and 3, 2 represents the tension; 3, 4, and 5, 65 the thread-guides; 6, the material in which the stitch is to be formed, and 7 the shuttle.

The arm a is mounted upon and rotates with a shaft B, which is supported in suitable bearings and which carries a pair of broken 70 gears b and b' of different diameters, which rotate therewith. The broken gears b and b' are engaged by a pair of similar gears d and d' on the shaft D, which is the power-shaft of the machine, or a shaft in operative connection 75 therewith.

It is evident that by varying the form and arrangement of gears b, b', d, and d' the angular velocity and variations in the angular velocity of the take-up rotated thereby may be 80 regulated with reference to the operation of the other features of the stitch-forming mechanism.

In connection with the foregoing description of the mechanism for actuating the arm a I desire to say that the same forms no essential part of the present invention, and any convenient or suitable mechanism may be substituted therefor.

The operation of the device is as follows: 90 Motion being imparted to the shaft D and the thread 8 being engaged with the take-up, as shown, the gears d and d' on shaft D, engaging with the gears b and b' on shaft B, impart to said shaft a fast-and-slow motion, 95 which in turn is imparted to the arm and take-up carried by said shaft. As the arm a and take-up a' rotate around the shaft B as a center the thread-guard a³, by means of the gears 9, 10, 11, and 12, is caused to revolve 100

about its center, and thus to retain a substantially fixed position with reference to the take-up, which, as shown in the drawings, is at the upper side of the take-up over the 5 thread thereon, and will therefore not interfere with the passage of the thread through the take-up nor permit it to become disengaged from or entangled with the take-up or thread-guard.

10 Having fully described my invention and its mode of operation, I desire to say that I do not consider my present invention as limited to the application thereof herein shown and described, for in so far as I am at present advised of the state of the art I am the first to provide a rotary or an oscillating take-up with a movable thread-guard which shall maintain its fixed angular position relative to the center of motion of the take-up during 15 the rotation or oscillation of the take-up.

I therefore claim as novel and desire to secure by Letters Patent of the United States—

1. In a take-up mechanism, a take-up movable about a center, means to actuate the 25 take-up, a movable thread-guard on said take-up and means to maintain the thread-guard in a substantially fixed angular position relative to the center of motion of the take-up, substantially as described.

2. In a take-up mechanism, a take-up movable about a center, means to actuate the take-up, and a thread-guard on said take-up movable about the center of motion of the 30

take-up, and about a center of motion of its own removed from the center of motion of the take-up, substantially as described. 35

3. In a take-up mechanism, a take-up, and means to rotate it about a fixed axis, and a rotating thread-guard on said take-up, movable about the axis of rotation of the take-up 40 and about its own axis, substantially as described.

4. In a take-up mechanism, a take-up and means to rotate it, and a movable thread-guard upon said take-up and gear connections between 45 said thread-guard and a fixed portion of the machine, whereby upon a rotation of the take-up the thread-guard will retain a substantially fixed angular position relative to the center of motion of the take-up, substantially as described. 50

5. In a take-up mechanism, the combination with a take-up arm movable about a center and means to actuate said arm, of a thread-roll on the outer end of said arm, a thread-guard on said arm and movable therewith, and means to maintain the thread-guard over and above the thread-roll during the movement of the take-up arm, substantially as described. 55 60

In testimony whereof I affix my signature in presence of two witnesses.

FREDERICK L. ALLEY.
